1 Claim

ABSTRACT OF THE DISCLOSURE

A switching device for a tape recorder. The device has switching levers respectively for recording, reproducing and rewinding, and corresponding switching bars for recording, reproducing and rewinding engaged by and actuated by said switching levers. A lock lever is engageable with each of said switching bars and locks each of said switching bars in its operational position when engaged therewith. A slide bar is engaged by and caused to slide by the operation of said rewinding switching bar, and obstructing levers are pivoted on said slide bar and obstruct, respectively, the movement of the recording switching bar and reproducing switching bar when the rewinding switching bar is in its operational position.

This application is a division of copending application Ser. No. 437,917 filed Mar. 8, 1965, now Patent No. 3,382,931 granted May 14, 1968.

This invention relates to tape recorders and more particularly to a switching device for a tape recorder wherein a multichannel magnetic tape is used.

More specifically, the invention concerns a tape recorder employing a multichannel magnetic tape having one special channel capable of recording, reproducing (playing back), and erasing any desired number of recorded channels, the tape recorder being capable of operations such as recording in the special channel various combinations of sounds reproduced from the recorded channels with entirely new, other sounds. The tape recorder of the invention is thereby highly useful for conversation practice and music practice.

Among known tape recorders of this general type, there is one type provided with the same number of heads as the number of channels. This known tape recorder, however, is disadvantageous in that not only is much space required for installing the heads, but also, since all of the heads are caused to contact a magnetic tape constantly, the wear of said tape is severe, whereby this tape recorder is unsuitable for use with tape having a large number of channels.

Furthermore, in order to protect the tape in this known tape recorder, the switching device for switching between recording, reproducing, and rewinding is, in general, so adapted that switching cannot be effected from rewinding directly to recording or reproducing, and the tape must always be positively stopped prior to the succeeding operation. Moreover, the known type of switching device is operated by a lever. Consequently, it has been difficult to carry out switching operations in a smooth manner in known tape recorders of this type wherein frequent switching between recording, reproducing, and rewinding must be carried out.

In view of the above considerations, it is a general object of the present invention to overcome the above

2

described difficulties accompanying known tape recorders of this type.

More specifically, it is an object of the invention to provide a lever type switching device having a simple construction and which is easy to operate. By this provision, in spite of the impossibility of switching from rewinding directly to recording or reproducing, switching directly between recording and reproducing can be accomplished in a smooth manner.

The nature, principle, and details of the invention, as well as further characteristic features and advantages thereof, will be more clearly apparent from the following detailed description with respect to a preferred embodiment of the invention when read in conjunction with the accompanying drawings in which like parts are designated by like reference characters, and in which:

FIG. 1 is a schematic circuit diagram illustrating the principle of the tape recorder according to the invention;

FIG. 2 is a plan view showing a multichannel magnetic tape suitable for use in the recorder of the invention;

FIG. 3 is a perspective view showing the general appearance of the tape recorder of the invention with its front lid opened;

FIG. 4 is a perspective view showing the general appearance of the tape recorder of the invention with its rear lid opened;

FIG. 5 is a perspective view, partially cut away, showing a unit comprising heads and a channel selection device for use in the tape recorder of the invention;

FIG. 6 is a perspective view of a switching device suitable for use in the tape recorder of the invention; and

FIG. 7 is a perspective view from a position below the view shown in FIG. 6.

Referring to the drawings, particularly FIGS. 1-4, the tape recorder embodying the invention is enclosed within a housing 1 provided with a front lid 1_a on one side and a rear lid 1_b on the opposite side. The lid 1_a protectively covers a control panel 1_c and control knobs and levers mounted thereon, namely a channel selection knob 2 having an indication marker 2_a to indicate channels marked on a channel scale 3 fixed to the panel 1_c, a volume adjusting knob 4 having an indication marker 4_a, a rewinding lever 5, a reproducing lever 6, a recording lever 7, and a lock lever 8. Said levers 5, 6, 7, and 8 are designed and grouped for efficient manipulation as will be described hereinafter. A desired channel is selected by turning the channel selection knob 2 to set marker 2_a at the symbol (numeral) corresponding to said desired channel.

The rear lid 1_b protectively covers a chamber 14_a containing an electric motor 9, a head block 10, a take-up reel 11, and a supply reel 12, the reels 11 and 12 accommodating a magnetic tape 13. The magnetic tape 13, as shown in FIG. 2, is provided with a large number of recorded channels 13_a and a special channel 13_b which is capable of being used for recording, reproducing, and erasing as described hereinafter. A partition 14 separates the chamber 14_a from another chamber which contains an amplifier device 15, a loudspeaker 16, and other parts.

The head block 10, which is shown in detail in FIG. 5, is secured to the interior side of the panel 1_c by screws 17 and 18 in a readily mountable and dismountable manner. The block frame structure essentially comprises an upper plate 20 and a lower plate 27 connected by parts such as tape guide shafts 28 and 29 and the shafts of tape guide rollers 30 and 31, said parts thus serving additionally as structural columns.

The channel selection knob 2 is fixed to the upper end of a shaft which is rotatably supported on the upper plate

20 and supports a gear 19 fixed thereto. Rotation of the knob 2 is transmitted through the gear 19 and a pinion 21 meshed therewith to a helical cam shaft 22 to which the pinion 21 is fixed. A click cam 26 which is also fixed to the cam shaft 22 is constantly contacted by a roller 24 provided at the free end of a click lever 23 pivoted at its other end on the upper plate 20 and rotationally biased in the counter-clockwise direction (toward the click cam 26) by a spring 25.

An erasing head 32 and a recording head 33 are fixedly mounted on the lower plate 27 in positions to contact only the special channel 13_b of the magnetic tape 13. A recording head 34 is mounted on a shifting plate 36 which is engaged with the helical groove of the helical cam shaft 22 and caused by the rotation of the shaft 22 to shift its position vertically along a guide shaft 35. Accordingly, the recording head 34 is capable of contacting all channels 13_a and 13_b of the magnetic tape 13.

Referring to FIGS. 6 and 7, the rewinding lever 5, the reproducing lever 6, and the recording lever 7 are supported pivotally at their respective lower ends on a shaft 37 fixed to a structural part of the housing 1 and are respectively biased by separate springs (not shown) in the direction opposite to that indicated by the arrow in FIG. 6. This lock lever 8 is provided with arms 8_a, 8_b, and 8_c in alignment for engagement with slots 38_a, 39_a, and 40_a, respectively, of the switching bars 38, 39, and 40, and when the switching bars 38, 39 and 40 are actuated in the direction of the arrow, they are thereby engaged and held in their respective operational positions.

A transverse slide bar 42 is supported in a position below the switching bars by columns 46 and 47 fixed to a structural part of the housing 1 and is biased by a spring 43 in the direction of the arrow. This slide bar 42 has a cam portion 42_a confronting the pin 38_b of the switching bar 38 and pivotally supports obstructing levers 44 and 45, which are biased by respective springs in the direction of the arrows shown in FIG. 7. These levers 44 and 45 are so disposed that their extreme ends can be placed in the paths of pins 39_b and 40_b, respectively.

The tape recorder of the present invention is operated in the following manner.

When recorded sound is to be reproduced and recorded in the special channel of the magnetic tape, and then a new sound is to be recorded through a microphone MIC, the recording lever 7 is first manipulated in the direction of the arrow, whereby the movement of this lever is transmitted through a suitable interconnecting mechanism (not shown) to close switches SW₁, SW₂, and SW₃. The channel selection knob 2 is turned until the marker 2_a coincides with the numeral on the scale 3 of the channel to be reproduced, whereupon the movement of the knob 2 is transmitted through the gear 19, pinion 21, and cam shaft 22, and the shift plate 36 is moved along the guide shaft 35. Accordingly, the reproducing head 34 is caused to contact the selected one of the recorded channels 13_a of the magnetic tape 13.

The sound of the recorded channel so reproduced by the reproducing head 34 is recorded through the recording head 32 into the special channel 13_b. During this step, the sound being reproduced can be listened to at the same time through the loudspeaker 16.

Next, the channel selection knob 2 is turned to cause the marker 2_a to coincide with a character N on the scale 3, whereupon the reproducing head 34 is caused to contact the special channel 13_b. Then through the microphone MIC, another sound is passed through the recording head 32 and recorded in the special channel 13_b.

When the rewinding lever 5 is thereafter manipulated in the direction of the arrow, the recording lever 7 is returned to its initial position, whereby the switches SW₁, SW₂, and SW₃ are opened, and, at the same time, the magnetic tape is run in the reversed direction and at high speed. Then, when the lock lever 8 is moved in the direc-

tion of the arrow, the rewinding lever 5 is also returned, and the electric motor 9 stops. When the reproducing lever 6 is moved in the direction of the arrow, the motor 9 operates, and the aforementioned two sounds recorded in the special channel 13_b are consecutively reproduced in sequence.

The lever type switching device shown in FIGS. 6 and 7 operates in the following manner. When the reproducing lever 6 is moved in the direction of the arrow, the arm 8_b of the lock lever 8 engages in the slot 39_a of the switching bar 39, whereby the bar 39 is locked against movement.

Next, when the recording lever 7 is moved in the direction of the arrow, the end of the recording switching bar 40 forces the arm 8_c of the lock lever 8 upwardly. Consequently, the arm 8_b is disengaged from the slot 39_a, and the switching bar 39 returns to its initial position, the recording switching bar 40 in turn being locked as the slot 40_a therein is engaged by the arm 8_c.

However, when the rewinding lever 5 is moved in the direction of the arrow, the transverse slide bar 42 is moved to its operational position in the direction opposite to the arrow by the pin 38_b on the switching bar 38, which has been moved to its operational position. Therefore,

even if either of the reproducing and recording levers 6 and 7 is moved in the direction of the arrow with the device in this condition, the pin 39_a on the switching bar 39 or the pin 40_b on the switching bar 40 will abut against the end of the obstructing lever 44 or 45, whereby the lever 6 and its bar 39 or the lever 7 and its bar 40 will be prevented from moving further. Accordingly, in this case the lever 6 or lever 7 must be manipulated after the lock lever 8 has been moved in the direction of the arrow to cause the rewinding lever to return to its initial position.

It should be understood, of course, that the foregoing disclosure relates to only a preferred embodiment of the invention and that it is intended to cover all changes and modifications of the example of the invention herein chosen for the purposes of the disclosure, which do not constitute departures from the spirit and scope of the invention.

What we claim is:

1. A switching device for a tape recorder comprising: three separate switching levers each movable between non-operational and operational positions, the first of said switching levers being for recording, the second of said switching levers being for reproducing, and the third of said switching levers being for rewinding; switching bars each movable by only one of said switching levers between corresponding positions; a locking lever movable to a lock position in which said lock lever selectively engages and locks any one of said switching bars when said switching bar is moved to its operational position; means urging said locking lever to its lock position; means urging each of said switching levers to its nonoperative position; said switching bars and said locking lever having cooperating means such that movement of any one switching bar to its operational position releases any other switching bar that is locked in its operational position; a slide bar engaged by and caused to slide in one direction by the movement of said rewinding switching bar to its operational position; means urging said slide bar in a direction opposite said one direction; and obstructing levers on slide bars and blocking, respectively, the movement of the recording switching bar and reproducing switching bar from movement out of their nonoperational positions when the rewinding switching bar is in its operational position.
